Glenn W. Tamm, Chicago, Ill., assignor to Binks
Manufacturing Company, Chicago, Ill., a cor-
poration of Delaware

Application June 19, 1942, Serial No. 107,241

Term of patent 7 years

To all whom it may concern:

Be it known that I, Glenn W. Tamm, a citizen of the United States and residing at Chicago, county of Cook, and State of Illinois, have invented a new, original, and ornamental Design for a Spray Gun for Spraying Coating Material or the like, of which the following is a specification, reference being made to the accompanying drawing, forming a part thereof.

Fig. 1 is a view in side elevation of a spray

gun for spraying coating material or the like, showing my design;

Fig. 2 is a top plan view of the same; and
Fig. 3 is a front view in elevation of the same.

I claim:

The ornamental design for a spray gun for spraying coating material or the like, substantially as shown.

GLENN W. TAMMEN.
